Filed Mar. 20, 1961, Ser. No. 110,835

13 Claims. (Cl. 137—185)

This invention relates to steam traps and more particularly to an inverted bucket type for draining condensate from a steam line and thereby maintaining said steam line full of hot dry steam. On accumulation of condensate in said trap in sufficient quantity to actuate the valve and open the discharge orifice, the condensate flows down under the edge of the bucket and up through the discharge orifice.

An object of the present invention is to increase the operational efficiency of a bucket type steam trap by constructing an assembly embodying an inverted bucket, a valve for the discharge orifice, and connections therebetween permitting a partial rotation of the bucket and valve in order to provide a different seating position of the valve in the outlet orifice to evenly distribute the wear of the valve and valve seat and thus provide for a more positive shut-off and the elimination of wire drawing.

Further objects of the present invention are to provide an improved steam trap by incorporating improved structural details serving to provide a simplified assembly facilitating the efficiency of the system and having a longer operational life as compared to some other traps as are presently available.

For a more detailed understanding of the invention, reference may be had to the accompanying drawings illustrating a preferred embodiment of the invention in which like parts are referred to by like reference characters throughout the several views, and in which

FIG. 1 is a vertical sectional view of a steam trap embodying the invention and showing the bucket buoyantly supported in said trap to maintain the discharge valve in closed position.

FIG. 2 is a similar sectional view showing the discharge valve fully opened.

FIG. 3 is a fragmentary sectional view showing the discharge valve just being opened.

FIG. 4 is a similar sectional view showing the linkage positioned and about ready to collapse and further retract the valve towards its fully opened position.

FIG. 5 is a transverse sectional view taken on the line 5—5 of FIG. 1.

FIG. 6 is a transverse sectional view taken on the line 6—6 of FIG. 1.

FIG. 7 is a sectional view of a steam trap embodying a modified valve actuating means showing the valve closed.

FIG. 8 is a similar sectional view showing the valve open.

FIG. 9 is a fragmentary sectional view illustrating the initial actuation of the valve, where same has just opened.

FIG. 10 is a transverse sectional plan view of the modified valve actuating means.

FIG. 11 is a vertical sectional view of a steam trap embodying a still further modified valve actuating means.

FIG. 12 is a plan view of a modified baffle means construction as viewed from line 12—12 of FIG. 11.

FIG. 13 is a detail sectional view of the baffle illustrated in FIG. 12 and taken on the line 13—13 of FIG. 12.

FIG. 14 is a fragmentary enlarged sectional view of the valve actuation means of FIG. 11 taken substantially on the section line 14—14 of FIG. 15.

FIG. 15 is a plan view of said valve actuating means as viewed from line 15—15 of FIG. 14, and

FIG. 16 is a fragmentary detail perspective view of the attachment of said valve actuating levers to the inverted back of said steam trap.

The steam trap illustrated in the accompanying draw-

2

ings comprises a casting forming a hollow body portion 10 closed by a head or cover 11. The hollow body portion provides a sump for collection of condensate drained from a steam line, and an inverted bucket 12 is disposed therein and is buoyantly supported in the liquid condensation when steam and/or air is trapped in the inverted bucket. The bucket 12 will of course sink to open the discharge orifice 14 when the steam or air is discharged from the bucket 12.

10 Referring more particularly to FIGS. 1 to 4 inclusive, it will be observed that the casting is provided with an inlet 15, which for simplicity is here shown as being connected by the cored passage 15a to the bottom of the trap. A stand pipe 16 is mounted at the inlet and extends upwardly part way into the hollow trap body and bucket 12. The head or closure 11 carries the discharge orifice 14 opening into a chamber 17 formed in the cover 11 and the body carries the discharge outlet 19 which is in open communication with the chamber 17. A valve 20 coacts with the discharge orifice 14 to open or close same and is supported in a guide bore 21 preferably carried by an inwardly located extension 23 of the head or closure casting, said extension being provided with a flat cam surface 24. The valve 20 extends below the cam face 24 and is loosely connected to a linkage assembly 25 which is in turn connected by a loose hook and eye connection with the bucket 12.

30 The linkage assembly 25 comprises a pair of opposite extending links 25a and 25b each having a hook portion 26 on one end and a preferably rounded cam edge 29 at the opposite end. Eyelets 28 carried by the bucket preferably at diametrically opposite points are engaged by the hooks 26 and serve to retract the valve 20 off its seat to open the discharge orifice when the bucket is no longer buoyant and sinks into the liquid condensate in said trap to thereby discharge the condensate from the trap through said discharge orifice and thence out through the outlet M. The lower edge of the bucket will then rest upon radially extending ribs 10a, or other suitable abutments, to space the lower edge of the bucket from the bottom of the trap to permit flow of condensate from the bucket interior into the trap body.

35 As the condensate is discharged, the flow of same through the inside of the inverted bucket, then under and outwardly of the lower rim of the bucket into the hollow trap body on its way to said discharge orifice, will cause a slight rotation of the bucket as the condensate impinges against baffles 30 preferably comprising downturned ears carried by a plate 29' which is secured to the underside of the bottom of the inverted bucket by welding or other suitable means. The valve 20 is pivotally secured to the levers or links 25a and 25b that extend normal to the axis of the valve and bucket, and thus as the bucket is partially rotated, the valve is also similarly rotated so that on being 40 again seated on its seat to close the discharge orifice, it is seated in a different position, insuring even wear of the valve and valve seat and longer life.

45 The operation of the steam trap is as follows:

Under ordinary operating conditions, the valve is closed because of the presence of steam in the trap bucket, said bucket being buoyantly supported in such condensate as has accumulated in the trap as shown in FIG. 1. As the steam escapes from the bucket through a small opening 50 and is absorbed in the condensate above the bucket, 50 it is replaced by condensate or steam as may be in the system above the bucket to which the trap inlet 15 is connected. If steam from said system enters the trap, the bucket remains buoyant and the valve remains closed. If condensate enters the trap, the bucket loses its buoyancy and opens the valve. If, after the valve is opened and condensate continues to enter the trap from said system, the bucket retains its non-buoyancy state and the

valve remains open. As soon as steam again enters the trap from said system, the steam is trapped in the inverted bucket and said bucket again becomes buoyant and closes the valve.

As described above, after the initial sinking of the bucket in the trap, it assumes a position as illustrated in FIG. 3, in which the valve is slightly open, but as additional condensate is drained into the trap, replacing the steam in the inverted bucket, the bucket continues to sink. As it moves farther away from the lower pointed end 31 of the valve (see FIG. 4) the links generally assume the position shown in FIG. 4, acting as levers to further retract the valve off its seat, and since the hooks 26 still engage the eyes 28 the whole linkage assembly suddenly collapses and assumes a position shown in FIG. 2, thus further retracting the valve off its seat, the valve and bucket being so dimensioned that said valve is still retained in the guide 21 at this lowermost position. The condensate continues to be discharged from the trap through the open discharge orifice as long as condensate continues to drain into the trap but as the steam again begins to flow into the trap from the steam line, it accumulates in the inverted bucket so that same again becomes buoyant and rises, carrying with it the valve until it again seats in the position shown in FIG. 1.

The above operation is automatically repeated as often as necessary to discharge the accumulated condensate. It will thus be apparent that as soon as steam floats the bucket, the valve is closed. Ordinarily, no steam ever reaches the discharge orifice, even when there is no condensate in the system, as the vacuum in the return line can cause no steam loss as the pressure differential across the discharge orifice holds the valve closed. Condensate drained into the trap from the steam line or system and condensation of the steam in said trap all builds up the level of the condensate in the trap, the entrapped steam in the bucket being gradually allowed to escape through the opening 50 until there is no longer a sufficient volume of steam in the bucket to float same.

It is noted that the valve 20 is coaxial with the inverted bucket, thus permitting a rotation of the bucket and valve, and the linkage assembly that loosely ties the valve to the bucket is positioned symmetrical with respect to the bucket and valve axis.

FIGS. 7 to 10 inclusive illustrate a modified type of linkage for connecting the bucket to the valve. The basic principle of operation remains the same, since the levers are different only in structure, and because they can be made of stampings which permit the fulcruming of the levers at various points offset from the axis of the valve, it facilitates valve operation as the pre-determined forces and values are such as to dictate the structural design and relationship of the interconnected parts.

This modified design is preferred and comprises a channel element 60 secured by suitable means to the valve as by a pin 61, said channel 60 comprising oppositely extending portions laterally offset from the valve axis. Forked levers 62 are respectively pivotally mounted on the channel 60 as by pins 63, said levers 62 each having one arm 62a extending away from the valve and loosely hinged by a hook and eye connection 64 to the inverted bucket, and oppositely extending arm 62b, which bear against the flat cam surface 24 of the trap, thereby retracting the valve off its seat as the bucket sinks in a manner similar to the action of linkage assembly 25 as illustrated in FIGS. 1 to 6 inclusive.

The alternative valve actuating means as illustrated in FIGS. 11 and 14 to 16 inclusive, comprises a modified lever arrangement including an improved means for attaching said levers to the bucket and valve.

The arrangement illustrated comprises a plate 70 secured to the valve stem 20a, the said valve stem having a shoulder 20b on which the plate 70 is seated and locked in position by a tension washer and a snap ring 71. The plate 70 is slotted at 72 to receive a return bent ear 73 of

a lever 74, whereby to loosely hinge the lever to the plate 70. It will be noted that the lever 74 is forked in plan and provides arms 74a extending inwardly from the loose hinge ear 73 to engage or contact with the flat under surface 24 of the valve stem guide 23.

An oppositely extending arm 74b of the lever terminates adjacent to the peripheral rim of the bucket 12a and is formed with a substantially U-shaped hook portion 75 providing an upwardly extending tip 76 and this hook portion is arranged to be loosely hooked or engaged in the eye or loop 77. The eye or loop 77 is substantially U-shaped and the legs 77a are extended through the holes 78 in the bottom of the inverted bucket 12a, which holes are adjacent to the peripheral rim of the bucket and are greater in diameter than the legs 77a, so as to provide means to vent the bucket of steam. The hook or eye 77 is preferably assembled to the bucket by having the leg extensions 77a bent to form end portions 78a originally formed to lie in a position as indicated by the dot and dash lines (FIG. 16) and after assembly, the end portions 78a are twisted to lie in the plane of the hook as shown in dotted lines in FIGS. 15 and 16.

The lever assembly of FIG. 11 functions similar to the lever assembly of FIGS. 1 and 10, and this construction makes it possible to provide two or more connections with the valve stem, such lever arrangements being preferably arranged symmetrical with respect to the valve stem axis.

FIGS. 12 and 13 illustrate a modified arrangement of 30 baffles, and comprises a plate 80, preferably circular, which is provided with punched out vanes or ears 81, said plate being welded, bolted or otherwise secured to the inside face of the bucket bottom.

While only a few preferred constructions are illustrated 35 and described herein, it will be quite apparent to those skilled in the art to which this invention pertains that various changes and modifications may be made without departing from the spirit of the invention or from the scope of the appended claims.

I claim:

1. A steam trap operable to automatically drain and discharge condensate from a steam line, and comprising a trap body having an inlet connected with the steam line and a discharge orifice, a valve for said discharge orifice, an inverted bucket disposed in said trap body and operable to trap steam in said bucket to float said bucket in the condensate as is accumulated in the trap and to thereby actuate the valve to close the discharge orifice, and motion multiplying linkage connecting said valve and inverted bucket and disposed symmetrically with respect to the bucket axis whereby to substantially align said valve with said bucket axis, and a guide for said valve axially aligned with the bucket axis aforesaid, said linkage comprising a pair of links pivotally connected with said valve and each link having oppositely extending arms, one arm bearing against an abutment and said other arm connected with said bucket, the movement of said bucket on sinking into the condensate in said trap actuating said links to open said valve, said links each being at all times 45 loosely connected with said bucket adjacent the peripheral edge thereof by a hook and eye connection, the extreme outer end of said links having an upwardly formed hook engaged by an eye carried by the bucket and operable to collapse said linkage and rest same on the bottom 50 of said inverted bucket, thereby fully retracting said valve from said discharge orifice in readiness to close the discharge orifice at such time as said bucket is again buoyantly raised by the accumulation of steam in said bucket.

2. A steam trap as defined in claim 1, wherein said 55 valve comprises an elongated stem portion supported in said valve guide while fully retracted from said discharge orifice, the stem portion having a flattened portion to which said links are pivoted.

3. A steam trap as defined in claim 1, wherein said 60 trap body carries said valve guide and provides a flattened

abutment extending in a plane normal to the axis of said valve stem, said inner ends of said links engaging said abutment in the operation of said links as levers to retract the valve from the said discharge orifice.

4. A steam trap as defined in claim 3 wherein said valve stem extends below the flattened abutment, and said links are pivoted to said valve stem at a point spaced below the plane of the flattened abutment.

5. A steam trap as defined in claim 4, where said link pivot means comprises a cross member secured to the lower end of the valve stem, and said links are each pivotally mounted on said cross member at points laterally offset with respect to the valve axis and symmetrically arranged relative to said valve axis.

6. A steam trap as defined in claim 5, wherein said links each comprise oppositely extending arms, one arm extending outwardly and loosely hinged to the bucket adjacent the peripheral rim thereof and the other arm comprising forked arm portions extending inwardly along either side of said cross member.

7. A steam trap operable to automatically drain and discharge condensate from a steam line, and comprising a trap body having an inlet connected with the steam line and a discharge orifice, a valve for said discharge orifice, an inverted bucket disposed in said trap body and operable to trap steam in said bucket to float said bucket in the condensate as is accumulated in the trap and to thereby actuate the valve to close the discharge orifice, and motion multiplying linkage connecting said valve and inverted bucket and disposed symmetrically with respect to the bucket axis whereby to substantially align said valve with said bucket axis, and a guide for said valve axially aligned with the bucket axis aforesaid, the linkage assembly connecting the valve and bucket comprises lever structure having oppositely extending lever arms, one arm loosely hinged to the valve stem structure and the other arm loosely hinged by a hook and eye connection to the bucket adjacent to the peripheral rim of the bucket, said eye portion of said connection comprising loops having legs extended through holes in the bottom of said bucket, the holes in said bucket having a cross-sectional area greater than the cross-sectional area of the legs to provide vent openings for said bucket for the escape of steam from the bucket interior.

8. A steam trap as defined in claim 7 wherein the legs of said loop connection terminate in lateral extending portions engaged with the under face of the bucket bottom to loosely secure said loop from disengagement with said bucket.

9. A steam trap as defined in claim 7 wherein said valve has a plate secured to the lower end thereof and disposed in a plane substantially normal to the valve stem axis, said plate having two or more slots symmetrically disposed about the valve stem, and said lever is provided with a downwardly turned ear arranged to be loosely hinged to said plate by a loose engagement with each of the slots aforesaid.

10. In a steam trap operable to automatically drain and discharge condensate from a steam line,

(a) a trap body having a trap chamber, an inlet adapted for connection with said steam line and a discharge orifice,

(b) a valve for said discharge orifice,

(c) an inverted bucket disposed in said trap chamber and operable to trap steam in said bucket to float same in condensate accumulated in said chamber whereby the axial position of said bucket with respect to said trap chamber is determined by the amount of steam in said trap chamber,

(d) said valve having one end engaged by the bottom of said inverted bucket during axial movement of said bucket caused by an increased accumulation of steam in said trap chamber whereby said valve is moved upwardly to close said discharge orifice when said bucket is floated,

(e) lost motion connection means comprising link elements operably connecting said bucket and said valve to open said orifice when said bucket sinks a predetermined distance in said condensate, and

(f) means carried by said link elements and operable after initial opening said valve upon initial sinking of said bucket to return said valve to a position engaging said bucket when said bucket has moved axially away from said valve a predetermined distance.

11. The steam trap as defined in claim 10 and in which

(a) said valve comprises a vertical cylindrical pin having upper and lower conically tapered ends,

(b) the bottom of said bucket has a central conical recess complementary to the lower end of said valve and providing a seat therefor whereby the axis of said bucket is normally retained on a line common to the axis of said valve.

12. The steam trap as defined in claim 10 and in which

(a) said link elements are two in number and each comprises a lever arm,

(b) each arm being pivotally retained near one end of said valve and the other end having an upwardly facing U-shaped slot,

(c) retainer elements being carried by said bucket and each comprising a downwardly facing U-shaped wire loop,

(d) said slots and wire loops being disposed in planes normal to one another and said wire disposed in said slot and loosely engaged therewith.

13. The steam trap as defined in claim 10 and in which

(a) said trap body has a stand pipe extending upwardly a considerable extent into said inverted bucket and occupying a large volume therein,

(b) a passage extending axially through said boss and connected with said inlet,

(c) the inner surface of the bottom of said bucket having baffles arranged to cause rotation of said bucket and discharge of condensate therefrom, said standpipe acting to force said condensate to move against said baffles as said bucket sinks in said condensate.
